SPRAY GUN

Felix Nieburg, Stockholm, Sweden, assignor to
Aktiebolaget Colorator, Stockholm, Sweden, a
company of Sweden

Application November 12, 1943, Serial No. 510,012,
In Sweden October 31, 1942

6 Claims. (Cl. 299—140.1)

1

The present invention relates to a method and device for spraying liquids, such as paints, lacquers, varnishes, molten metal or the like, atomized to a spray jet by means of gas or air for surface coating purposes.

The main object of the present invention is to change, in connection with the indicated type of spraying, the cross section of the liquid-gas jet (here called the "paint-air jet") by means of suction produced in the vicinity of said jet, particularly in the vicinity of the place where the jet discharges from the spraying device, said suction being adjustable and thereby enabling a continuous or step-wise adjustment of the cross section of the liquid-gas jet.

A further object of the invention is to achieve said suction by means of one or more separate gas or air jets, designated hereinbelow as "suction jets" or "deformation jets," flowing in diverging directions relative to the paint-air jet or parallel with an at some distance from said jet. As the diverging suction jets have higher outflow velocity than the paint-air jet there occurs a more or less injector-like suction action tending to increase the width of the paint-air jet. Due to this difference in velocity a space of reduced pressure is formed between the suction jets and the paint-air jet, causing the width of the paint-air jet to be increased in the direction towards the suction jets.

Starting from a paint-air jet of originally circular cross section, a further object of the invention is to increase the width of said jet in one or more directions by means of the suction jets so that a more lengthy cross section or a cross section of increased width in one or more directions is obtained. By arranging several diametrically opposed suction jet orifices in two planes perpendicular to each other an increase of the width of the paint-air jet in horizontal or vertical direction may be obtained as the suction jets disposed in one of said planes or the other, respectively, are operated.

A still further object of my invention is to achieve very great jet widths by causing the suction jets to act upon a paint-air jet, which is originally somewhat compressed or flattened by means of a slotted nozzle, for instance. In such a case I dispose the outflow orifices of the suction jets diametrically opposed in positions corresponding to the direction of the major axis of the substantially elliptical cross section of the paint-air jet, and the action of the suction jets then cause an increase of the width of the paint-air jet in the direction of said major axis. In

2

this way great jet widths may be obtained. A further object of the invention is to arrange two suction jets diametrically opposed in the direction of the minor axis of the cross section also, so as to change the elliptical cross section towards a more circular shape.

A further object of the invention is to control the influence of the suction jets and consequently the width of the paint-air jet by adjustment of the outflow direction and/or of the pressure, quantity or the outflow velocity, respectively, of the suction jets.

My invention also comprises combinations with methods and means in which auxiliary gas jets are used for flattening or compressing the cross section of a liquid-gas jet. Thus, it is an object of the invention to further widen an originally flattened paint-air jet in the direction of the major axis by means of suction or deformation jets, and then by changing the outflow direction of said deformation jets and/or by means of separate pressure deformation jets again to compress the shape of the paint-air jet until it is more or less circular. The change of shape may be effected completely continuously or stepwise.

Since the outflow velocity of the suction jets is higher than the outflow velocity of the paint-air jet, the suction jets act more or less as propulsion jets according to U. S. Patent No. 2,247,000 dated June 24, 1941. Consequently, the invention also includes embodiments involving different combinations with the invention according to said patent. However, separate propulsion jets may also be used together with or independently of the suction jets.

The accompanying drawings illustrate as examples some embodiments for carrying out the method according to the invention.

Figure 1 is an external view of a spray gun according to the invention,

Figure 2 is a longitudinal section of the spray head,

Figure 3 is a front view of the spray head according to Figure 2,

Figure 4 is a diagrammatical longitudinal section of a part of the spray head on a larger scale and illustrates the "flat-jet" position of the deformation nozzle in which the deformation jets act as suction jets,

Figure 5 is a similar longitudinal section and illustrates the position in which the deformation jets act as pressure jets,

Figures 6 and 7 are a longitudinal section and a front view, respectively, of another embodiment of the spray head,

Figures 8 and 9 are similar views of a further embodiment, and

Figures 10 and 11 similar diagrammatical views of a modification.

In the several figures the same reference characters refer to similar parts.

With reference to Figures 1-3 compressed air is supplied from a suitable source to the spray gun (Fig. 1) through the pipe connection 1, and paint under pressure is supplied through the pipe connection 2 communicating with the paint receptacle 3. The supply of paint is controlled by means of a paint needle 4 (Figure 2) which is slidably mounted and is actuated in a known manner by means of a trigger member 5 (Figure 1). Preferably, the needle opens inwardly and in Figure 2 it is shown in its closed position. The needle may be guided by a sleeve 7. From the pipe connection 1 the air enters a chamber 8 from which it flows through a passage 9 and rectifiers 10 to an atomizing passage 11 formed in front of the paint nozzle 12 in the atomizing nozzle 13. The velocity of this stream of air is controlled by means of a rotatable choke valve 14. The casing 15 of the spray head is attached to the body 16 of the spray gun by means of a threaded sleeve or nut 17.

From chamber 8 the air is also supplied through bores 18 in the body 16 and ports 19 in the casing 15 to a chamber 20 within the deformation nozzle 21 which has projections 22 and is screwed into the casing 15 so that by turning or rotating the nozzle 21 in one direction or the other the position of the said nozzle may be adjusted axially. The rotation of the nozzle 21 may be limited by means of a stop screw 23 screwed into casing 15. Similarly, the whole spray head or hood may be rotated relative to body 16 in order to adjust the position of the major axis of the spray jet as will be described, and this rotation may be limited by means of a stop screw 24 screwed into body 16. A spring 25 may be provided to establish a modified frictional resistance against the rotation of the nozzle 21 so that the latter will not be displaced unintentionally from its position.

The external end of the atomizing nozzle 13 is located after or externally of the mouth of the deformation nozzle 21, viewed in the direction of flow.

If the paint needle 4 is retracted from the closed position shown in Figure 2 the paint from the paint nozzle 12 will enter the atomizing passage 11 in which it is atomized by means of the air entering the passage 9 and uniformly divided over the whole periphery of the said atomizing passage 11 by means of the rectifiers 10. The mixture of air and paint discharges through a slot-like discharge orifice 25 or a narrow slit in the atomizing nozzle 13 so that the paint-air jet flowing out through the slot 25 will obtain the shape of a flat jet more or less elliptical in cross section. By rotating the spray head or hood 15 the slot may be adjusted from vertical position to horizontal position or any inclined position therebetween.

The air supplied to the chamber 20 in the manner described is intended to serve as deformation or shaping air, and to this purpose the outer surface of a member 26 has two diametrically opposed curved recesses 27, and two likewise diametrically opposed plane and inclined recesses 28. Between the recesses 27 and the inclined front wall 34 of the deformation nozzle 21 there are left openings 33 for the discharge

of air from chamber 20. By adjusting the nozzle 21 axially the direction or the quantity of the discharged air may be controlled.

Through passages 30 in the member 26 the chamber 20 also communicates with a chamber 31 located around the nozzle 13. From the latter chamber air may discharge through an annular opening 32. This air serves as blowing air to keep the outer portions of the nozzle 13 and the member 26 free from drops of paint as described in United States patent application Serial Number 367,091 (now U. S. Patent No. 2,297,497).

In order to insure that the recesses 27 and 28 occupy accurate positions relative to the plane of slot 25 the member 26 and the nozzle 13 are interconnected by means of a guide pin 54 and associated with an inner extension 55 of the nozzle 13 by means of a nut 29.

The velocity of the air in the passage 11 may be controlled by means of the choke valve 14, preferably in such a manner that the velocity of the mixture of paint and air discharging from the slot 25 is the same or higher than the velocity of the air discharging through the openings 32 and 33.

The operation of the sprayhead illustrated in Figures 2 and 3 will now be described with reference to Figures 4 and 5.

In Fig. 4 the front wall 34 of the deformation jet nozzle 21 has such a position relative to the recesses that the deformation air supplied from the chamber 20 discharges in diverging directions through the openings 33 along the paths B. The paint-air jet discharging through the slot 25 of the atomizing nozzle 13 would have the path indicated by the lines A and the elliptical cross section I, provided that said paint-air jet is not influenced by the deformation jets B. By the suction action of the deformation jets B, however, the width of the cross section of the paint-air jet is extended, so that the cross section of the paint-air jet takes the resulting path indicated by the lines C and the elliptical lengthy shape indicated at II so as to form a wide or flat jet.

The maximum width of this wide jet depends upon several factors, for instance the curvature of the recesses 21, the inclination of the wall 34 and the position of said wall relative to the axis of the atomizing nozzle 13, the angle 35 between the wall 34 and the cylindrical surface of the member 26, and the shape of the paint-air jet produced by the slot 25.

Fig. 5 shows the effect of opening the air outlet area formed between the inclined plane recesses 28 and the inner wall 56 of nozzle 21 by means of forward displacement of said nozzle. Thereby the deformation jets take a converging direction, as illustrated by the lines B¹, and compress the paint-air jet discharging from the atomizing nozzle, which originally has a path confined by the lines A¹ and a cross section indicated by the ellipse I¹, so that said jet takes a more circular resulting shape II¹ confined by the lines C¹. Between said extreme positions of the shaping jet nozzle 21 relative to the atomizing nozzle 13 which produce jets having wide or circular cross section, respectively, the deformation jet nozzle may be set into any position, and consequently continuous adjustment from wide to circular jets may be obtained.

Figs. 6 and 7 illustrate a further embodiment. In this embodiment the paint needle 4 opens outwards but the atomizing may be effected in main-

ly the same manner as in the two embodiments already described. Furthermore, the deformation or shaping of the atomized paint-air jet by means of the suction jets is effected in two steps. In the proximity of the atomizing nozzle 13 there is a first deformation nozzle 41 screwed into a separating wall 42 of the casing 15 so that the nozzle 41 may be displaced axially so as to control the direction and/or the quantity of the air discharging through the openings 43. These openings may be formed in substantially the same manner as the openings 33 in Fig. 2. The air to the openings 43 is applied from a chamber 44 communicating with the passage 18 through the port 19. Behind and outside the nozzle 41 there is a second deformation nozzle 45 which is screwed adjustably into the casing 15 and contains a chamber 46 communicating with a separate source of compressed air through a pipe connection 48 having a control valve 47. The suction air supplied to the chamber 46 discharges through openings 49. The suction air jets discharged through openings 43 and 49, respectively, are adjusted so as to produce a greater suction action for the jets through openings 49 than for the jets through openings 43.

If the paint-air jet discharging from the slot 25 is not influenced by any suction jets it takes the path A and the cross section I. The suction jets B from the openings 43 produce a first increase of the width of said jet A so that it assumes the cross section II, provided that there were no further suction jets. A further widening of the cross section of the jet A, however, is effected by the suction jets D discharging from the openings 49 so that the paint-air jet finally obtains the resulting wide cross section III and the path C. Thus the shaping or deformation of the wide jet C is effected step-wise. Of course, more than two steps may be used in order to attain the desired result.

According to Figs. 8 and 9 the deformation nozzle 50 has a grip surface 51 and is provided with recesses 52, arranged diametrically opposed. The suction jet nozzle 50 is attached to the casing 58 by means of a nut 53 mounted so as to allow the nozzle 50 to be turned without operating the nut. The atomizing nozzle 59 has a discharge opening 60 which here is shown as a circular orifice. An annular recess 61 is formed on the nozzle 59 in the vicinity of the front edge of the nozzle 50. It is thus clear that turning of the nozzle 50 will result in a turning of the plane containing the recesses 52 and thus also the discharge openings between these recesses and the annular recess 61.

In the position shown in Fig. 8 the paint-air jet discharging through the opening 60 would have the path A and the circular cross section I if not influenced by any suction jets. The air discharging through the opening between the recesses 61 and the recess 52 as indicated at the lines B influence by suction the paint-air jet so that the latter obtains the elliptical cross section II with vertical major axis and takes the path C. If the deformation nozzle 50 is turned by means of the grip surface 51, for instance through an angle of 90°, which may be performed without turning the nut 53, the paint-air jet will likewise be turned 90°, so that the major axis of the elliptical cross section of the paint-air jet will be horizontal as indicated at IV. Between the position II and IV the said major axis may be set in any desired inclination.

During this adjustment of the position of the

major axis of the paint-air jet the angle of divergence of the suction jets B may be kept constant but it may also be varied by displacing the deformation nozzle 50 axially or turning the nut 53 so that the front edge of said nozzle 50 changes its position in relation to the recess 61.

Figs. 10 and 11 show an example of changing the paint-air jet from elliptical cross section to circular cross section by means of suction jets.

- 10 The suction jets B discharge from openings formed between the front edge of the deformation nozzle 62 and recesses 64 on the external surface of the atomizing nozzle 63, while the paint-air jet discharges from the discharge slot 65 (here shown in horizontal position). The recesses 64 are arranged in the plane of the minor axis of the slot 65. It is clearly understood that the original elliptical cross section I of the paint-air jet A will be influenced by the suction jets B so that the paint-air jet will assume a more or less circular cross section II and follow the resulting path C.

As many changes could be made in the above method and construction and many apparently widely different embodiments of the invention could be made without departing from the scope thereof, as defined by the following claims, it is intended that all matter contained in the above description shall be interpreted as illustrative and not in a limiting sense.

What I claim is:

1. In a device for spraying liquids, for coating purposes, an atomizing nozzle for atomizing the liquid by means of gas to form an atomized liquid-gas jet, and an auxiliary nozzle arranged in juxtaposition to said atomizing nozzle, said auxiliary nozzle having a discharge passage defining with the juxtaposed portion of said atomizing nozzle an outwardly-directed outlet for a gas-suction jet, the said passage being outwardly positioned relative to the said atomizing nozzle and having a jet-directing wall inclined outwardly relative to and beyond the outermost normal contour-defining limits of the liquid-gas jet, a common source of supply of air for said atomizing nozzle and said discharge passage, said discharge passage being smaller than said atomizing nozzle, whereby the velocity of the jet through said passage is higher than that of the jet through the atomizing nozzle and whereby the gas-suction jet is emitted in such a direction in relation to the contour of said atomized jet as to increase substantially the initial width of the latter jet by suction.

2. In a device for spraying liquids, for coating purposes, an atomizing nozzle for atomizing the liquid by means of gas to form an atomized liquid-gas jet, and an auxiliary nozzle arranged in juxtaposition to said atomizing nozzle, said auxiliary nozzle having a passage defining with the juxtaposed portion of said atomizing nozzle an outlet for a gas-suction jet, said discharge opening being outwardly positioned relative to the said atomizing nozzle and having a jet-directing wall inclined outwardly relative to and beyond the outermost normal contour-defining limits of the liquid-gas jet, a common source of supply of air for said atomizing nozzle and discharge passage, said discharge passage being smaller than said atomizing nozzle, whereby the velocity of the jet through said passage is higher than that of the jet through the atomizing nozzle and whereby the gas-suction jet is emitted in such a direction in relation to the contour of said atomized jet as to increase substantially the initial width

of the latter jet by suction, portions of the surface of said atomizing nozzle which are juxtaposed to said auxiliary nozzle extending in different directions, and said auxiliary nozzle being displaceable relatively to said atomizing nozzle, whereby the direction of flow of said gas-suction jet may be varied by displacing said auxiliary nozzle relatively to said portions.

3. In a device for spraying liquids, for coating purposes, an atomizing nozzle for atomizing the liquid by means of gas to form an atomized liquid-gas jet, a supply conduit for compressed gas communicating with said atomizing nozzle, and an auxiliary nozzle communicating with said supply conduit and arranged in juxtaposition to said atomizing nozzle, said auxiliary nozzle having a passage defining with the juxtaposed portion of said atomizing nozzle and outwardly directed outlet for a gas-suction jet, the said auxiliary nozzle being outwardly positioned relative to the said atomizing nozzle and having a jet-directing wall inclined outwardly relative to and beyond the outermost normal contour-defining limits of the liquid-gas jet, said discharge passage being smaller than said atomizing nozzle, whereby the velocity of the jet through said passage is higher than that of the jet through the atomizing nozzle and whereby the gas-suction jet is emitted in such a direction in relation to the contour of said atomized jet as to increase substantially the initial width of the latter jet by suction, and a control valve in said supply conduit for controlling the discharge velocity of said atomized jet.

4. In a device for spraying liquids, for coating purposes, an atomizing nozzle for atomizing the liquid by means of gas to form an atomized liquid-gas jet, and an auxiliary nozzle arranged in juxtaposition to said atomizing nozzle, said atomizing nozzle having a passage defining with the juxtaposed portion of said atomizing nozzle an outwardly directed outlet for a deformation jet in one position of said auxiliary nozzle, the said passage being outwardly positioned relative to the said atomizing nozzle and having a jet-directing wall inclined outwardly relative to and beyond the outermost contour-defining limits of the liq-

uid-gas jet, a common source of supply of air for said atomizing nozzle and said discharge passage, said discharge passage being smaller than said atomizing nozzle, whereby the velocity of the jet through said passage is higher than that of the jet through the atomizing nozzle and whereby the said deformation jet is emitted in such a direction in relation to the contour of said atomized jet as to increase the initial width of the latter jet by suction, and the said passage defining with the juxtaposed portion of said atomizing nozzle and inwardly directed outlet for said deformation jet in another position of said auxiliary nozzle whereby the said deformation jet is emitted in such a direction in relation to the contour of said atomized jet as to decrease the initial width of the latter jet by pressure.

5. The structure according to claim 4, said auxiliary nozzle containing a plurality of said discharge passages for said gas deformation jets.

6. The structure according to claim 4, said auxiliary nozzle being rotatably mounted on said atomizing nozzle and containing a plurality of said discharge passages for deformation jets, and means to turn said auxiliary nozzle and said discharge passages relative to the axis of said liquid-gas jet to control the direction of said deformation jets for adjusting the cross-section of the liquid-gas jet.
